CLAIM

The ornamental design for a breast pump, as shown and described.

DESCRIPTION

FIG. 1 is a front, right side perspective view of the four portions of breast pump in separate state, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a partially enlarged view of the left bottom component in FIG. 1; and,

FIG. 9 is a partially enlarged view of the right bottom component in FIG. 1.

The broken lines in the drawing depict portions of the breast pump that form no part of the claimed design.
